UNITED STATES PATENT OFFICE

92,800

DESIGN FOR A KEY CONTAINER

Jack Galter and Arthur Waller, Chicago, Ill.

Application May 16, 1934, Serial No. 51,813

Term of patent 3½ years

To all whom it may concern:

Be it known that we, JACK GALTER and ARTHUR WALLER, both citizens of the United States, and residents of Chicago, in the county of Cook and State of Illinois, have invented a new, original, and ornamental Design for a Key Container, of which the following is a specification, reference being had to the accompanying drawing, forming a part thereof.

Fig. 2 is a similar view of the rear face thereof; and

Fig. 3 is a side elevational view of the same.

We claim:

The ornamental design for a key container substantially as shown.

Signed at Chicago, in the county of Cook, and State of Illinois, this 14th day of May, 1934.

JACK GALTER.
ARTHUR WALLER.
